UNITED STATES PATENT OFFICE.

DANIEL F. MCGILL, OF PORTLAND, OREGON, ASSIGNOR TO MCGILL BOILER CLEANER COMPANY, OF PORTLAND, OREGON, A CORPORATION.

APPARATUS FOR CLEANING BOILERS.

1,124,634.

Specification of Letters Patent. Patented Jan. 12, 1915.

Application filed September 16, 1911. Serial No. 649,623.

To all whom it may concern:

Be it known that I, DANIEL F. MCGILL, a citizen of the United States, residing at Portland, in the county of Multnomah and State of Oregon, have invented certain new and useful Improvements in Apparatus for Cleaning Boilers, of which the following is a specification.

This invention relates to improvements in boiler cleaners and has for its object to provide a circulatory system which will cause a sluggish flow of the water at a certain point so as to permit a deposit of the particles carried in suspension by the water.

15 A further object is to provide, in a circulatory system through boilers, a means of precipitating the sediment carried in suspension by the water and to collect it in a suitable tank where it can be removed, and 20 thereby prevent the deposit of scale on the interior of the boiler.

With these objects in view the invention consists in the novel construction and arrangement of parts illustrated in the accompanying drawing, in which—

25 Figure 1 is a perspective view of a boiler showing my improved circulatory system as applied. Fig. 2 is a detail sectional view showing a section of pipe arranged to contain a chemical reagent for precipitating the sediment held in solution.

Referring to the drawing in detail, the character 1 represents a boiler of usual construction having the fire box 1^a. From the 35 rear end of the boiler, at a point near the top, but below the water level, is inserted one or more pipes 7, which connect with risers 9 each containing a cut-off valve 8, and uniting above the boiler into the single pipe 10. This pipe is united by means of a T-joint having a cut-off 10^a in its outer end, with the horizontal pipe 11 extending to a point near the opposite end of the boiler. Here the pipe 12 leads down to the horizontal pipe 5, with which it is connected by 45 means of a T-joint and which extends to a convenient place near the front end of the boiler; and by means of vertical pipe 4 it is connected in the upper end of the precipitating tank 2, resting on the pedestal 23. Alongside of the entering pipe 4 is a vertical outlet pipe 6, which connects with horizontal pipe 13 leading to the front end of the boiler, and there, by means of a T-joint 55 carrying a cut-off valve 15 in its outer end,

connects with a suitable union 16 from which one or more transverse arms 14 extend. From each arm or pipe 14 there is dropped a pipe 17 which divides near the bottom of the boiler into branches 19, each of which contains a cut-off valve and is provided with a terminal member 20, which enters the boiler near the lower water line, thus completing the circuit. It is obvious that the position of the pipes leading from the tank to the boiler may be varied to suit the conditions and the convenience of the operator. It is essential only that the water leaves the tank at the upper end near the inlet pipe and that it enters the boiler near the lowest level.

The chamber 5 of the pipe is provided with a portion 5^a which extends forward of the pipe 4, and with another portion 5^b extending back of pipe 12. Within the pipe 5, 60 which is preferably larger than the other pipes of the system, is placed a sheet or tube 29 of aluminum, though another suitable reagent may serve the same purpose. This is made of equal length with pipe 5 65 and the cap 31 prevents longitudinal movement therein. Apertures 24 and 26 are provided in the tube 29 to register with the openings in the T-joints 30 and 25 respectively. The cap 31 is provided with a central aperture to receive the rod of the brush 28, and the packing 32 prevents leakage therethrough. By use of handle 3 the brush may be reciprocated so as to keep the surface of the aluminum free from deposits of 70 sediment. The extensions at each end of the tube 5 afford room for the brush to rest so that it will not interfere with the circulation of the water, when not in use. The system having been filled with water and 75 the valve 10^a closed, the other valves being open, the application of heat to the boiler, as in any hot-water system, will cause the water to rise through the higher outlets 7, 80 passing through pipes 11—4 and entering tank 2. Here the larger volume of water will move more slowly, thus allowing the particles carried by the more rapid current to settle on the bottom, the upward motion of the water toward the exit pipe 6 not being sufficiently rapid to hold the particles in suspension. This arrangement of the inlet and outlet pipes in the tank also facilitates 85 the deposit of sediment carried in the water. The inflowing water tends to prevent the 90

formation of a current toward the outlet, and also tends to force toward the bottom the particles of sediment.

The formation of scale in boilers is due to the presence in the water of sulfates of calcium and magnesium and other substances which have an affinity for aluminum, and other chemical reagents. I have, therefore placed in the section of pipe just preceding the precipitating tank a lining of aluminum which, acting on compounds of the elements indicated, disintegrates them causing the residue to flow into the tank where it is deposited as silt, which will not form scale, and which may be drawn off at proper intervals by means of faucet 22. It will be seen that by use of this system the scale forming substances will be carried from the water and not allowed to form on the boiler, which will thus remain clean. Old boilers containing water which has thus been deprived of the scale forming substances, will be relieved of the scale by a similar disintegration thereof.

Having thus described my invention, what I claim is—

1. In a system of the class described, the combination with a boiler, of a tank positioned adjacent thereto, a pipe rising from the upper end of the tank, a pipe leading from the boiler at a point slightly below the water-level and rising above the boiler, a cut-off valve in said riser, a pipe leading from said riser toward said tank, a section depending therefrom, a pipe connecting said depending portion with that rising from the tank and having its inner wall covered with aluminum, a brush reciprocating therein, a pipe leading from the upper end of said tank at a point adjacent the entrance pipe of said tank and entering said boiler below the water level, a cut-off valve in said return pipe, and a draw-off valve in the lower end of the tank.
2. In a system of the class described, the combination with a boiler, of a tank positioned adjacent thereto, a pipe leading from the boiler at a point slightly below the water level and rising above the boiler, a cut-off valve in said riser, a pipe leading from the riser toward the tank, a chamber connecting the last named pipe with the upper end of the tank and having its inner wall covered with a different metal serving as a chemical reagent, a pipe leading from the upper end of the tank at a point adjacent the entrance pipe of said tank and entering the boiler below the water level, a cut-off valve in said return pipe, and a draw-off valve in the lower end of said tank.
3. In a system of the class described, the combination with a boiler, of a tank positioned adjacent thereto, a pipe rising from the end of the tank, a pipe leading from the boiler at a point slightly below the water

level and rising above the boiler, a cut-off valve in said riser, a pipe leading from the riser toward said tank, a section depending therefrom, a chamber connecting said depending portion with that rising from the tank the ends of which project beyond the said connected pipes, said chamber having its inner wall covered with aluminum, a brush reciprocating in said chamber, a pipe leading from the upper end of the tank at a point adjacent the inlet pipe of said tank and entering the boiler below the water level, a cut-off valve in said return pipe, and a draw-off valve in the lower end of said tank.

4. In a system of the class described, the combination with a boiler of a tank positioned adjacent thereto, a pipe rising from the end of the tank, a pipe leading from the boiler at a point slightly below the water level and rising above the boiler, a cut-off valve in said riser, a pipe leading from the riser toward said tank, a section depending therefrom, a chamber connecting said depending portion with that rising from the tank the ends of which project beyond the said connected pipes, a pipe leading from the upper end of the tank at a point adjacent the inlet pipe to said boiler, entering same at the lower water level, a cut-off valve in said return pipe, a draw-off valve in the lower end of said tank, an aluminum lining secured in said chamber, and a brush adapted to reciprocate therein for cleansing said lining.

5. In a system of the class described a boiler, a feed-water system supplying water thereto, a chamber formed in said system, and an aluminum lining secured in said chamber.

6. In a system of the character described, a boiler, a settling tank, a conduit connecting the boiler and settling tank, and a second conduit connecting the boiler and settling tank and including an aluminum conduit receiving the water therethrough to decompose the boiler-scale forming substances held in suspension in the water.

7. In a system of the character described, a boiler, a settling tank, a supply conduit connecting the settling tank and boiler, and an outlet conduit connecting the settling tank and boiler and having a substantial portion of its inner wall formed of aluminum and receiving the water therethrough for decomposing the boiler-scale forming substances held in suspension by said water.

8. In a system of the character described, a conduit adapted to be connected with a boiler at a plurality of points to form a circulatory passage for the water in the boiler, and an aluminum conduit-section connected in said conduit and receiving the water therethrough for decomposing the boiler-scale forming substances held in suspension in the water.

9. In a system of the character described, a boiler, a settling tank, conduits connecting the settling tank and boiler, and a chemical reagent of a different character from the material of one conduit, arranged therein and secured to the inner wall thereof, to receive the water therethrough, without perceptibly retarding its flow, for decomposing the boiler-scale forming substances held in suspension by the water.

10. In a system of the character described,

a boiler, a conduit connected therewith and having an interior lining of aluminum to receive the water therethrough, a second conduit connected with the boiler, and a 15 shell connecting the two conduits.

In testimony whereof I affix my signature in presence of two witnesses.

DANIEL F. McGILL.
